US00D935712S

(12) **United States Design Patent** (10) **Patent No.:** **US D935,712 S**
Wang (45) **Date of Patent:** **** Nov. 9, 2021**

(54) **SWEEPING MACHINE**

(71) Applicant: **Shenzhen Hua Xin Information Technology Co., Ltd.**, Guangdong (CN)

(72) Inventor: **Minyong Wang**, Guangdong (CN)

(73) Assignee: **Shenzhen Hua Xin Information Technology Co., Ltd.**, Shenzhen (CN)

(**) Term: **15 Years**

(21) Appl. No.: **29/772,548**

(22) Filed: **Mar. 2, 2021**

(30) **Foreign Application Priority Data**

Nov. 17, 2020 (CN) 202030696375.2

(51) **LOC (13) Cl.** **15-05**

(52) **U.S. Cl.**

USPC **D32/21**

(57) **CLAIM**

The ornamental design for a sweeping machine, as shown and described.

DESCRIPTION

FIG. 1 is a perspective view of a sweeping machine showing my new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion of FIG. 1;

FIG. 10 is an enlarged view of a portion of FIG. 3;

FIG. 11 is an enlarged view of another portion of FIG. 3;

FIG. 12 is an enlarged view of a portion of FIG. 4;

FIG. 13 is an enlarged view of another portion of FIG. 4; and,

FIG. 14 is an enlarged view of a portion of FIG. 8.

The broken lines in the figures depict portions of the sweeping machine and form no part of the claimed design.

1 Claim, 14 Drawing Sheets
